ABSORBENT PACK FOR BOTTLES

Grace Fiero, New York, N. Y., assignor to Venus Corporation, New York, N. Y., a corporation of New York

Application November 21, 1932, Serial No. 643,579

5 Claims. (Cl. 150—52)

My invention relates to a pack envelope or casing for fragile liquid containers, such, for instance, as glass bottles.

In making journeys, persons frequently find it necessary or desirable to take along toilet liquids, lotions, medicines and the like. The bottles containing these liquids are usually put into valises, handbags, trunks, and the like along with various articles of clothing and personal accessories. Due to jostling crowds, rough handling and transport, bottles carried in this manner are frequently broken with the result that the liquid contents thereof saturates and soils the clothing and other articles within the carrying bag or piece of luggage.

The purpose and object of my invention are to provide for a bottle of liquid an encasing device embodying a novelly constructed pack or wrapping adapted, in the event the bottle is broken, to absorb the freed liquid and to keep the same within the encasing device so that the contents of the carrying bag or luggage cannot become soiled or damaged by reason of bottle breakage.

Another object of the invention is to provide a construction of the character described, in which the absorbent pack or wrapping may be readily removable for drying or for replacement.

With the foregoing and other objects in view, the invention consists in the construction and relative arrangement of parts so combined as to coact and cooperate with each other in the performance of the functions and the accomplishment of the results herein contemplated, and the invention comprises in its evolution the simple and practical example illustrated in the accompanying drawing, wherein similar reference characters designate corresponding parts throughout the several views, and in which:—

Figure 1 is a side elevational view of the bag showing partially broken away a pack envelope embodying the invention;

Fig. 2 is a perspective view of the pack or wrapping portion of the device, removed from the envelope;

Fig. 3 is an enlarged transverse section taken on the line 3—3 of Fig. 2; and

Fig. 4 is a vertical sectional view taken on the line 4—4 of Fig. 1.

Referring with more particularity to the accompanying drawing, the device of my invention comprises in general an envelope or casing section *a* in the form of a bag body and an absorbent pack or wrapping section *b* in the form of a bag body made of a size to fit wholly within and to be enclosed by the said section *a*.

To carry forward the objects of the invention, the said section *a* should be capable of containing liquid, and to this end it is produced either from rubber or waterproof material. In assembling and making up this bag body section, the same may consist of a single piece of material or of several pieces connected in water-tight manner by any well-known vulcanizing process, sewing or the like. In the present embodiment, the section *a* is represented as consisting of two layers of material 10 and 11 of which the outer layer 10 consists of flexible yielding fabric, while the inner layer 11 consists of thin rubber material. This bag section *a* is provided at its top with a mouth-opening 12 of a size sufficient to permit installation or removal of the bag section *b* and as well of the bottle *c*, it being observed from Fig. 4 that when these parts are assembled for use, the bag section *b* is encased by the section *a* while the bottle *c* is in turn encased by the section *b*.

The absorbent pack or wrapping bag section *b* comprises a double-bodied device including an outer bag body *b'* and an inner bag body *b''*. It will be noted from the disclosure of Figs. 3 and 4 that the inner bag body *b''* is of a size to provide a space or chamber 13 between itself and the outer bag body *b'*. Said space or chamber 13 is filled with an absorbent material, such for instance as cotton, cotton batting, rubber sponge, or the like. In the present embodiment, I illustrate absorbent cotton 13' packed within the chamber 13 between the inner and outer bag bodies *b''* and *b'*. Said bag bodies *b'* and *b''* are made from thin rubber material or any suitable waterproof material; either in one piece or in several pieces suitably vulcanized together or united by sewing. These two bag bodies at their top ends, are united at 14 (Fig. 4) so as to provide a mouth-opening 15 through which to insert or remove the bottle *c*. In the present embodiment, the bag body *b''* is represented as consisting of a layer of thin rubber material 16 and a layer of thin fabric 17, it being noted that the layer of rubber defines the bottle chamber 18, whereas the fabric layer 17 comes adjacent the absorbent cotton. The outer bag body *b'* is herein represented as consisting of a flexible yielding fabric 19 faced at its inner side adjacent the cotton batting with a thin rubber lining 20. It may be noted here in passing that either one or both of the bag bodies *b'* and *b''*, may consist of flexible yielding fabric having a coating or sheathing of thin rubber.

According to an important feature of my in-

vention, the rubber layer 16 of the inner bag *b*'' is provided with apertures 21 in spaced-apart relation. Through this provision and with the layer 17 being composed of liquid permeable material, if the bottle *c* is broken, the liquid contents thereof released in the bottle chamber 18 will gradually pass through the openings 21 and seep through the layer 17 to the chamber 13 where it will be imbibed by the absorbent cotton. It will be recognized that the double-bodied absorbent pack or wrapping section *b* and the encasing envelope section *a* provide substantial protection for the bottle *c*, safeguarding the same against breakage; and further that this construction and arrangement, in the event the bottle *c* should become broken, provide means for taking in or imbibing the liquid contents of the bottle wholly inside the envelope or casing section *a*.

In carrying the invention forward, a pack closure *d* in cooperation with the inner section *b* is provided at the top end of the bottle. This pack closure, like the section *b*, comprises a double-bodied structure including an outer flexible wall 22 and an inner flexible wall 23, connected and arranged to provide an intervening space or chamber which is filled with absorbent cotton or the like. This pack closure, as shown in Fig. 4, is made in the form of a cap so as to surround the top end of the bottle and come like a surrounding apron about the neck *c*' of the bottle and well below the cap *c*'' or other closure for the outlet end of the bottle. It will be noted that the inner wall 23 of this pack closure is provided with spaced openings 24 through which liquid may pass to the absorbent cotton filling the chamber between the walls 22 and 23. At or near its lower end, this pack closure may be equipped with means whereby to be drawn tightly around the neck *c*' of the bottle; and in the present instance I show a draw string 25 suitably engaged with the device for this purpose. The draw string may consist either of elastic or of non-elastic material; and in place of such string, I may, if desired, employ a resilient wire spring adapted to hold the pack closure tightly around the bottle neck and to be expanded sufficiently to pass over the bottle rim and cap.

As will be evident, this pack element *d* is formed to serve as a cover for the top end of the bottle, the same having the function of absorbing any liquid which may leak through or around the cap or stopper provided at the top end of the bottle. As an absorbent covering for this purpose, the pack element *d* may, if desired, be employed on the bottle without the use of either casing section *a* or wrapping section *b*.

For the mouth-opening 15 of the section *b*, I may provide a flexible flap 26 adapted, when the bottle has been inserted in the bottle chamber and fitted with the pack closure *d*, to be stretched across the mouth-opening 15 and tucked into the crevice or space between the pack closure device and the adjacent portion of the section *b*, as shown in Fig. 4.

Any suitable means may be provided for closing the mouth-opening 12 of the envelope or casing section *a*. The means herein disclosed for this purpose comprises a spring clip 27 which may be applied as shown in Fig. 4 so as to maintain the opposite marginal portions or lips 28 of the mouth opening in tight frictional contact along a considerable distance so as to avoid any leakage of liquid from the construction.

It will be recognized that the invention herein disclosed evidences in its simplest form an en-

cased absorbent pack with openings or passages leading from the bottle chamber to the surrounding absorbent material so that if the bottle is broken the freed liquid will gradually pass to the absorbent material to be taken in or imbibed thereby.

Adjacent their top ends, the casing section *a* and pack section *b* may be detachably connected by a lacing 29 which is interengaged with loops 30 on the outer face of the bag body *b*' and with suitable eyelets 31 in the material of the casing section *a*. This lacing connection may, as herein shown, be at one side only of the structure, or it may be provided entirely around the same.

With the spring clip 27 detached and the flap 26 drawn to one side, the bottle *c* with the pack closure *d* can be readily inserted or removed from the bottle chamber 18. In the event, through the breaking of the bottle, the absorbent becomes wet, the pack section *a* may be removed in its entirety for drying or replacement upon withdrawing the lacing 29, an operation which can readily be accomplished from the outside of the structure.

In describing my invention with the aid of the views above referred to, I desire to point out that I intend such views as merely illustrative of an example whereby my invention may be applied in practice, and I do not limit myself to the precise construction and arrangement of parts shown. The description of the views is, therefore, to be broadly considered as including substitute arrangements and constructions which are the obviously equivalent of those shown.

I claim:—

1. An absorbent pack accessory for a bottle or the like comprising a flexible bag having a chamber for accommodating the bottle and a mouth-opening through which to insert the bottle into the chamber, said bag including an outside wall impervious to liquid and at the inner side thereof an absorbent packing for taking up liquid in the event of the breaking of the bottle, an absorbent pack element insertable through the mouth-opening and shaped to encircle the end of the bottle so as to pack and hold the bottle in place, said element being disposed within said packing, and means for closing and sealing the mouth opening at the exterior side of the bag, closing of the mouth opening coactively tightening said packing about said element to hold the bottle against movement.

2. An absorbent pack accessory for a bottle or the like comprising a flexible bag having a chamber for accommodating the bottle and a mouth-opening through which to insert the bottle into the chamber, said bag including an outside wall impervious to liquid and at the inner side thereof an absorbent packing for taking up liquid in the event of the breaking of the bottle, an absorbent pack element insertable through the mouth-opening and shaped to encircle the end of the bottle for packing and holding the bottle in place and absorbing liquid, and a liquid impervious outer wall engageable about said element and fixed to the inner side of the bag for closing the end of the chamber adjacent the mouth-opening at the inside thereof.

3. An absorbent pack accessory for a bottle or the like comprising a flexible liquid impervious bag shaped to contain the bottle in its chamber and having at one end a mouth-opening through which to insert the bottle, a layer of absorbent material overlying the inner face of the bag, a perforated liner protecting the absorbent material, means insertable through the mouth-opening

for completely encircling the end of the bottle and affording a packing to close the inside of the mouth-opening and engage and contact the liner, and means for closing the mouth-opening exteriorly of said packing.	5.	A pack accessory for a bottle or the like comprising a flexible bag having a mouth-opening through which to insert the bottle into the chamber of the bag, a flexible closure insertable through the mouth-opening to close the same on the chamber side and shaped to encircle the neck and end of the bottle, said bag and closure each consisting of outer and inner walls with absorbent packing interposed between the same, each outer wall being impervious to liquid and each inner wall being perforated to permit liquid to pass therethrough from the chamber for absorption by the packing, a flap for the mouth-opening adapted to afford and maintain an engagement between the bag and closure, and a covering for the bag for closing the mouth-opening at the outside thereof.	80
4. A pack accessory for a bottle or the like comprising a flexible bag having a mouth-opening through which to insert the bottle into the chamber of the bag, a flexible closure insertable through the mouth-opening to close the same on the chamber side and shaped to encircle the neck and end of the bottle, said bag and closure each consisting of outer and inner walls with absorbent packing interposed between the same, each outer wall being impervious to liquid and each inner wall being perforated to permit liquid to pass therethrough from the chamber for absorption by the packing, a flap for the mouth-opening adapted to afford and maintain an engagement between the bag and closure, and a covering for the bag for closing the mouth-opening at the outside thereof.	10		85
10 the mouth-opening to close the same on the chamber side and shaped to encircle the neck and end of the bottle, said bag and closure each consisting of outer and inner walls with absorbent packing interposed between the same, each outer wall being impervious to liquid and each inner wall being perforated to permit liquid to pass therethrough from the chamber for absorption by the packing, and means for closing the mouth-opening at the outside thereof.	15		90
